MECHANICAL SWEEPER

Howard A. Olds, San Francisco, and Ira M. Wells and Ward Wells, Oakland, Calif., assignors to Spears-Wells Machinery Company, Inc., Oakland, Calif., a corporation of California

Application November 18, 1938, Serial No. 241,236

4 Claims. (Cl. 15—83)

This invention, a mechanical sweeper, is of the vehicular type customarily used for sweeping streets and highways.

Many difficulties have been encountered in the operation of street sweepers due mainly to obtrusional build-up back of the brush, and the pick-up of bricks, tin cans, boards and other bulky or heavy objects by the brush.

In connection with obtrusional build-up, the brush, usually of the rotary type, obviously encounters many different types of material, including dust, mud, and solid weighty or bulky objects, and where no means is provided for keeping the path of flight clear from the brush to the hopper or other field or deposit, the sweepings gradually build up behind the brush or in the direction of discharge until the sweepings form a complete obstruction in the path of flight, and the sweeper gradually loses efficiency until, if the obstruction is not removed, it becomes entirely inoperative.

In connection with the encountering of solid objects, such as stones and bricks by the brush, these objects may merely be cast back a short distance, this immediately starting a serious obstruction in the path of flight of the sweepings.

Some existent types of sweepers are provided with drags or conveyors. However, in connection with wet material, such types of clearing devices become encrusted and will eventually become completely clogged so that they cease to function, and furthermore, they are very difficult and inconvenient to clean. Such devices are easily made substantially inoperative by muck, and may be completely wrecked by a brick or other bulky object being cast into them by the brush. They also offer no assistance to the brush in the projection of the sweepings, such as by suction or the increase in the velocity of air.

It is the purpose of this invention to eliminate all of the above mentioned difficulties through the introduction of a flight booster or high speed flail, which boosts the speed of flight of sweepings discharged by the brush to insure their deposit at a remote point, and, through the medium of the flailing action, maintain the flail free of encrustation; and to operate the flail at a peripheral speed preferably at least equal to the peripheral speed of the brush, so as to urge, and increase the speed of flight of slower moving sweepings through both, the action of the high speed flails, and the suction created at the bottom of the brush and acceleration of the air set up by the flails in the direction of flight of the sweepings; and also to obviate the possibility

of wrecking the booster by making the flails of a flexible or resilient material, such as rubber or belting, or similar suitable material, and to additionally hinge the flails, so that the booster cannot become blocked or be wrecked by an obstruction, such as a brick.

The objects of the invention are as follows:

First, to provide a mechanical sweeper with a flight booster for boosting the flight of sweepings discharged by the brush, so as to cause their deposit at a point considerably remote from the brush, and to maintain the path of flight clear of obstruction.

Second, to operate the booster at a peripheral speed sufficiently high as to insure projection of the sweepings to a sufficiently remote point and to insure suitable increase in speed of slower moving sweepings to project them to the same remote point.

Third, to provide the booster with flails of flexible material to make them self-cleaning and to obviate the possibility of wrecking of the booster or causing inoperativeness thereof through cooperation with heavy objects.

Fourth, to hingedly mount the flails so as to doubly insure safety from breakage, and to provide for a vibrational effect through deflection from the normal radial position in which the flails are urged through the medium of centrifugal force, thus causing release of mud or other encrustation on the flails and associated structure.

Fifth, to introduce, through the high peripheral speed of the flails, a high velocity of air movement from the brush and along the path of flight to augment the flight of sweepings from the brush, past the flail, to the hopper.

Sixth, to provide adjustment for the flails radially, to compensate for wear at the outer edge of the flails.

Other objects and advantages of the invention will become apparent as the following description is read on the drawing forming a part of this specification, and in which similar reference characters are used to designate similar parts in the several views of which;

Fig. 1 is a side elevation of a mechanical sweeper shown fragmentarily, with the invention installed therein.

Fig. 2 is a fragmentary longitudinal sectional elevation through the mechanical sweeper, showing the relation of the booster to the brush and to the path of flight, and is taken on a line just inside the near wall of the sweeper chassis or body.

Fig. 3 is an enlarged sectional elevation through the booster, and is taken on a line 3-3 of Fig. 4.

Fig. 4 is a front elevation of the booster, with portions broken away to show the internal construction; and,

Fig. 5 is an enlarged fragmentary sectional view of the flail adjusting means.

The usual mechanical sweeper includes a chassis or body 10 which is vehicularly mounted, as on wheels 11, for transporting the sweeper along a road or pavement 12. Dumping means, or a hopper 13 which can be lifted out and dumped is provided for reception of sweepings from the brush which is of the usual type, consisting of a hub 14 mounted on a shaft 15 which is rotatably mounted in the chassis 10, and which brush is provided with the usual sweeping elements, such as bristles 16. This brush is driven by any of the well known means (not shown), such as by one of the wheels 11, or by means of the motor used for propelling the vehicle, or by a separate motor.

All of the elements so far mentioned are well known in the art, and therefore do not form a part of the invention, except in combination with, or in relation to, the other elements set forth in the following description.

The booster, which forms the essential element of this invention, consists of a rotatably-driven element comprising a shaft 17; a spider 18 fixedly secured to each end of the shaft 17 and having a plurality of equi-angularly-spaced arms 19 having each a bearing formed adjacent the outer end thereof. The opposite ends of the shaft 17 are rotatably supported by the chassis 10 in spaced relation to the brush 16. An enlarged hub 20 spans the space between the spiders 18, and acts to confine the path 21 of flight of sweepings 22 to a predetermined angle relative to the horizontal, and to concentrate said path for delivery of sweepings within a predetermined field in a location remote from the brush, and also forms a rebound element for the flails to be later described.

A shaft 23 spans the space between the spiders 18 for each pair of related arms 19 and has its opposite ends rotatably mounted in the respective bearings provided adjacent the outer ends of these arms, and these shafts are maintained against axial movement by any well known suitable means, such as collars, or in some manner similar to that indicated at 24.

A flail 25 is provided for each shaft 23 and supported thereby, and preferably consists of a flat blade or strip of flexible or resilient material, such as rubber, or belting, although other material may be substituted.

Each flail is secured to a support member, such as a structural angle 26, forming a rigid reinforcement for the inner edge of the blade, the balance of the blade being free to flex. These flails are attached to the shafts 23 by means of a plurality of bolts or studs 27 for each flail, the studs having one end fixedly secured in the angle 26 and the other end passing through a suitable aperture 28 formed through the shaft 23 and secured in adjusted position by the opposed nuts 29 and 30. These bolts in addition to forming supports for the flails, form the adjusting means for adjusting the flails radially to compensate for wear.

A hood or guard 31 is formed about the top peripheral path of the flails and extends sub-

stantially into cooperative relation to the brush 16 as indicated at 32.

As will be understood, the brush 16 and booster 3 can be mounted in any desired position, either 5 at the front end, rear end, or intermediate the length of the vehicle, and may be driven by any suitable means.

In this case, the sweeping elements are indicated as mounted intermediate the length of the vehicle. The driving means for the booster is shown as consisting of a sprocket 33 secured on the end of the booster shaft 17, a second, or driving sprocket 34 being mounted on the brush shaft 15, and a chain 35 cooperating between these sprockets, and which driving means is driven by one of the means previously inferentially referred to, as through a chain 36 which will be herein considered as the driving means.

In operation, with the vehicle suitably propelled and the brush 16 driven in the direction of the arrow 37, the sweepings are thrown from the bottom of the brush as indicated by the path of flight 38 of the sweepings.

The booster 3 is driven in the same direction, and preferably at the same, or greater peripheral speed than the brush, and the flails 25 are normally maintained radially under the influence of centrifugal force, as shown in Fig. 3, and operate directly in, and with the path of travel 39 of the sweepings, whereby loss of energy in the sweepings is immediately augmented or boosted, both, by direct action of the flails on the sweepings, and also by the velocity of the air 39 induced by these flails, which tends to maintain the speed of flight of the sweepings constant or increase the speed thereof, from the time they leave the brush until they pass through the path of the flails, and thus, the sweepings, instead of partially depositing close to the brush as indicated at 40, are drawn, forced, and boosted in their flight to deposit at the remote point, as in the hopper 13, as indicated at 22.

In the event that the sweepings are wet, they will have a tendency to adhere to the flails 25; however, due to the fact that the flails are formed of flexible material, the sweepings will normally be released from the flails through the flexing and centrifugal actions, as also through striking of the flails on the hub and through vibrational movements set up as the flails strike heavier particles or objects.

In the event that larger objects, such as sticks, stones or bricks 41 are cast into the path of the flails, the flails upon striking such objects will rebound to pass over them while successively providing a beating action to move the object beyond their influence, and if the objects are sufficiently large or heavy, the flails will rebound and strike the hub 20 as indicated by the dotted position 25' indicated; thus the flail will be thoroughly freed of adhering material and will additionally function to free the hub 20 of excessive accumulation, and, instead of clogging or wrecking, the objects have the beneficial effect of cleaning the booster.

The floor 42 as illustrated is formed tangentially to the periphery of the brush and is plane throughout its extent and entirely free of obstructions, depressions or pockets, and is also tangent to the peripheral path of the outer edges of the flails, and forms an obstructionless wall defining one side of the path of flight of materials projected from the periphery of the brush, and extends from a point adjacent to the brush to a remote point beyond the rotary conveyor.

Any sweepings discharged by the brush at an inclination greater than that indicated at 21, will either be deflected by the booster, or stopped and returned by the hub 20 or guard 31, 32, and the instant upper portion of the booster.

The tendency to form obstruction in the path of flight of the sweepings; deleterious encrustation with consequent decrease in efficiency; as also the possibility of breakage or wrecking of the sweepings removal elements or the flight booster, are completely obviated, and the sweeper will continue to function with highest efficiency, removal of the sweepings 22 occasionally being all that is required.

It will be understood that variations in construction and arrangement of parts, which variations are consistent with the appended claims, may be resorted to without detracting from the spirit or scope of the invention, or sacrificing any of the advantages thereof.

We claim:

1. A flight booster for trajected materials comprising a rotary conveyor to be driven in the same direction and at a speed at least equal to, and operating in the path of said materials, and consisting of a shaft; a spider mounted adjacent each end of said shaft; a drum surrounding said shaft and extending between said spiders and forming means for restricting the path of flight of said trajected materials to a predetermined course; said spiders each having a plurality of equi-angularly-spaced arms and a bearing formed adjacent the outer end of each arm; a hinge shaft rotatably mounted at its opposite ends in related bearings of the respective spiders; and a flail rigidly attached to each shaft and adapted to beat on said drum to clear the drum and flails of adhering materials.

2. A flight booster for trajected materials comprising a shaft; a spider mounted adjacent each end of said shaft; said spiders each having a plurality of equi-angularly-spaced arms and a bearing formed adjacent the outer end of each arm; a hinge shaft rotatably mounted at its opposite ends in related bearings of the respective spiders; and a flail rigidly attached to each hinge shaft and comprising each a flexible blade, a reinforcing element of rigid material affixed to the inner

edge of each blade; and studs securing the reinforcing element to the hinge shaft and forming means for radial adjustment of the blade.

3. A flight booster operating in cooperative relation to a rotary brush and comprising; a plane floor formed tangentially to the lower periphery of said brush; a rotary conveyor having a plurality of flails for operating in the path of flight of materials when trajected by said brush, and operating in cooperative relation to said plane floor and in spaced relation to said brush and functioning to boost the speed of flight of the trajected material to or above its initial trajected speed for deposit of the material without change of its normal course other than its trajectory, to a remote location; and in which said rotary conveyor includes a hub with the inner edges of the flails radially spaced from the periphery of said hub and pivotally mounted to permit the outer edges of the flails to strike and rebound from the hub under impact applied to the outer edge by obstructions, for loosening adhering material from the flails and hub.

4. A flight booster operating in cooperative relation to a rotary brush and comprising; a plane floor formed tangentially to the lower periphery of said brush; a rotary conveyor having a plurality of flails for operating in the path of flight of materials when trajected by said brush, and operating in cooperative relation to said plane floor and in spaced relation to said brush and functioning to boost the speed of flight of the trajected material to or above its initial trajected speed for deposit of the material without change of its normal course other than its trajectory, to a remote location; and in which said rotary conveyor includes a hub having a spider at each end and a plurality of arms on each spider and a bearing formed in each arm, and with the flails pivoted in said bearings and spanning between the spiders, and with the inner edges of the flails spaced from the periphery of the hub a distance less than the distance from the pivot to the outer edge of the flail for rebound of the flail on the hub to free adhering material.
